UNITED STATES PATENT OFFICE.

ANDREW P. TALLMADGE, OF WASHINGTON, DISTRICT OF COLUMBIA.

GAS-ENGINE SPARKER.

No. 818,926.

Specification of Letters Patent.

Patented Feb. 27, 1906.

Application filed March 18, 1905. Serial No. 250,829.

To all whom it may concern:

Be it known that I, ANDREW P. TALLMADGE, a citizen of the United States, residing at Washington city, District of Columbia, have 5 invented certain new and useful Improvements in Gas-Engine Sparkers; and I do hereby declare the following to be a full, clear, and exact description of the invention, such as will enable others skilled in the art to 10 which it appertains to make and use the same.

This invention relates to certain improvements in sparking devices for explosive-engines; and the objects and nature of my invention will be readily understood by those 15 skilled in the art in the light of the following explanation of a construction shown in the accompanying drawings as an example from among other arrangements within the spirit and scope of my invention.

20 It might be here stated that an object of the invention is to provide an exceedingly-simple improved device which can be readily applied to certain types of explosive-engines now in use and whereby the sparks can be 25 easily and quickly advanced or the sparking device can be so set as to cause the sparks to occur at the desired time with relation to the movement of the piston.

The invention consists in certain novel features in construction and in arrangements or 30 combinations of parts, as hereinafter more fully set forth and explained.

35 Referring to the accompanying drawings, Figure 1 is an elevation of the working parts of a sparking device including my invention, the cylinder and other working parts of the engine not being shown. Fig. 2 is a detail or detached perspective view of my device or attachment. Fig. 3 is a longitudinal sectional 40 view of the device or attachment shown in Fig. 2.

45 My attachment or device is particularly adapted for use on the stationary explosive-engine such as disclosed by United States Patent No. 746,406, issued December 8, 1903, to J. S. Thurman, and in the drawings I have shown only the connections or means for actuating the sparking points. In the engine of said patent a swinging and reciprocating 50 rod carries a tripping-dog to periodically trip means for moving the movable sparking point. This actuating-rod is slideable through a rocking or oscillating guide block or head, which practically constitutes the fulcrum for 55 said actuating-rod. This guide-block con-

tains a spring-held follower pressed toward the rod to permit outward yielding thereof in case of accidental back throw of the engine; but the block has no means for shifting the fulcrum-point of the actuating-rod for 60 the purpose of advancing the spark. My attachment is substituted for said oscillating guide-block of the patent just referred to and is provided with means for changing the fulcrum or position of said actuating-rod to 65 vary the time of the spark with respect to the position of the piston of the engine.

In the drawings, 1 is a plate secured to the head of the engine-cylinder, (not shown,) and this plate carries the rod 3, projecting into the cylinder to form the stationary sparking point, and also the rocking shaft 5, which within the cylinder is provided with the movable sparking point, (not shown,) co-operating with said stationary point, as in said patent, to produce the spark on the separation 75 of the two points.

7 is an arm rigid with the rocking shaft 5. 11 is an arm loose on shaft 5 and at one end having extension 13, bearing against 80 expansion-spring 14. At its opposite end arm 11 is provided with the projected end or finger 12 and with a lateral extension 17, to the outer end of which retractile spring 18 is secured, the opposite end of said spring 18 85 being secured to the arm 7 to yieldingly hold a lateral projection of said arm 7 against the arm 11. The spring 14 yieldingly holds the arms 11 and 7 in their normal positions, (see Fig. 1,) with the arm 7 against buffer 9 of rigid 90 stud 10.

22 is the actuating-shaft for the sparking device, and 20 is the actuating-rod reciprocated and swung by said shaft and at one end having eccentric connection with said shaft 95 through the medium of a crank arm and pin 21. The actuating-rod is provided with the tripping-dog 19, which has an elliptical path of movement and is adapted to engage the projecting end or finger 12 and move the 100 same to contact the sparking points.

23 is a stud projecting from the plate 1, and 24 is a rocking or oscillating block mounted to rock on said stud, any suitable means being provided to confine said block on said 105 stud. At one end the block 24 is formed with the journal or bearing hole or opening 25, extending therethrough to receive said stud 23. The block is elongated and formed with a longitudinal slideway open at the op- 110

posite sides of the block and closed at its outer end by a plate 26, secured to the ends of the opposite side walls of the block.

27 is a guide-box for the actuating-rod 20 and through which the same reciprocates. This box 27 extends transversely through said slideway of the oscillating block 24 and is loosely confined therein and adjustable longitudinally thereof. This box 27 is preferably recessed across its side edges to receive the opposite side walls of the block 24 and to form shoulders fitting the longitudinal edges of said side walls to hold the box against transverse movement in the block. The box 27 is preferably formed in two sections or halves longitudinally of the bore or bearing opening 28 therethrough for the rod 20. These sections of the box 27 are suitably secured together, as by machine-screw 29, so that the sections can be separated when necessary. I usually clamp a suitable liner or liners 30 between the two sections, so that wear can be taken up as the reciprocating rod 20 wears the bearing-opening 28. Suitable means are provided to move the guide-box 27 longitudinally of the oscillating block to vary the position of the tripping-dog 19 with respect to the projecting end or finger 12 and to hold or lock said box in the desired position. As an example of means which can be employed for this purpose I show a screw-threaded rod 31 arranged longitudinally of the block and passing loosely through the plate 26 and at its inner end rigid with the box 27.

32 is a wing-nut at the outer face of plate 26 and screwed on the outer end of the threaded rod 31 and by means of which the threaded rod and the box can be moved longitudinally of the oscillating block. 33 is an expansive spring coiled around the threaded rod and compressed between the box 27 and the plate 26 to hold the nut 32 and the box in proper position and to force the box inwardly of the slideway when the nut is unscrewed or loosened.

If desired, the plate 26 can be formed with a series of radial grooves or depressions 34 around the opening for the threaded rod and 50 the nut with a radial rib or edge 35 to fit in any one of said grooves, and thereby lock the nut in the desired adjustment and whereby the adjustment can be more accurately effected and determined as the rib snaps from 55 groove to groove.

In Fig. 1 the box 27 is shown adjusted about to normal position to cause the engaging end of the tripping-dog to travel in the elliptical path indicated by the lower dotted 60 path and in the direction of the arrows and so that the dog will engage the finger 12 and swing the same to the left, and thereby swing the arm 7 and bring the movable sparking point into contact with the fixed point and so 65 that the dog will slip past finger 12 about at

the dotted line b, and thereby permit the arms and movable point to return to normal position, thereby causing the igniting-spark.

If the engine speeds up so that it becomes desirable to economize fuel and attain maximum power by advancing the spark, it is merely necessary for the operator to turn the nut 32 in a direction to move the box 27 outwardly the desired distance to cause the dog to trip the finger 12 at an earlier point in its path. For instance, the box 27 can be adjusted outwardly to cause the engaging end of the dog to move in the upper path shown by dotted lines in Fig. 1, in which the dog will trip at the point a, thereby advancing the spark with respect to the movement of the piston.

It is obvious that by employing my attachment a wide range of adjustment is provided for either retarding or advancing the spark to suit various conditions and that the construction is exceedingly simple and durable and very easily operated.

The attachment can be applied to various types of engines and can be very readily applied to engines of the Thurman type now in use by simply substituting my attachment for the guide-block of the Thurman engine.

It is evident that various changes and modifications might be resorted to in the forms, arrangements, and constructions of the parts described without departing from the spirit and scope of my invention. Hence I do not wish to limit myself to the exact construction shown.

What I claim is—

1. As an article of manufacture, the spark-advancer comprising a block adapted to be mounted and rock on a journal and having a longitudinal slideway, a box through which the sparker-actuating rod is adapted to reciprocate, said box confined in said slideway, and means for adjusting said box longitudinally of said slideway and holding the same in the desired adjustment, substantially as described.

2. An explosive-engine spark-advancer comprising a block having a bearing on which the block is adapted to oscillate, a box confined to and movable longitudinally of said block, said box having a bore through which the sparker-actuating rod reciprocates, and a threaded rod and nut for adjusting said box and holding the same in the desired position longitudinally of the block.

3. A spark-advancer comprising a block having a bearing on which the block is adapted to oscillate with a swinging and reciprocating sparker-actuating rod, said block having a longitudinal slideway, a box confined in said slideway to slide longitudinally thereof and having a bore receiving and through which said rod reciprocates, a threaded rod for moving said box in one direction and extending longitudinally of the block, a spring yieldingly

pressing said box in the opposite direction, and a nut on said rod for moving the same longitudinally.

4. A spark-advancer comprising a block having a longitudinal slideway, a plate closing the outer end thereof, a box extending through and longitudinally movable in said slideway and formed with a longitudinal bore therethrough, said box being formed of longitudinal sections removably secured together, a threaded rod confined to said box and extending outwardly through said plate, a spring compressed between said plate and the box, and a nut on the outer end of the rod at the outer face of said plate.

5. In an explosive-engine, in combination, sparking mechanism, a reciprocating and swinging actuating-rod provided with a tripping-dog for actuating said mechanism, means for actuating said rod, and an oscil-

lating block provided with a box in which said rod is confined and through which the same reciprocates, and means for moving said box to move said rod laterally and for locking the same in the desired adjustment. 25

6. In an explosion-engine igniter, a movable electrode, an oscillatory tripped member, a reciprocating engine-operated tripping-rod, a guiding bearing-box surrounding said rod, a rocking block carrying said box, 30 and provisions for shifting said box laterally with respect to the path of movement of the rod.

In testimony whereof I affix my signature in presence of two witnesses..

ANDREW P. TALLMADGE.
